(57) **CLAIM**

I claim the ornamental design for a battery operated toothbrush, substantially as shown.

DESCRIPTION

FIG. 1 is a perspective view of the battery operated toothbrush.

FIG. 2 is a top plan view thereof.

FIG. 3 is a bottom plan view thereof.

FIG. 4 is a side elevational view thereof.

FIG. 5 is the opposite side elevational view thereof.

FIG. 6 is a front elevational view thereof; and,

FIG. 7 is a rear elevational view thereof.
